(57) **CLAIM**

The ornamental design for a terminal tractor, as shown and described.

DESCRIPTION

FIG. 1 is a front perspective view of a terminal tractor, showing our new design.

FIG. 2 is a rear perspective view of the terminal tractor of FIG. 1.

FIG. 3 is a front view of the terminal tractor of FIG. 1.

FIG. 4 is a left side view of the terminal tractor of FIG. 1.

FIG. 5 is a right side view of the terminal tractor of FIG. 1.

FIG. 6 is a rear view of the terminal tractor of FIG. 1; and, FIG. 7 is a top view of the terminal tractor of FIG. 1.

Any broken lines in the figures form no part of the claimed design.

1 Claim, 7 Drawing Sheets
